No. 37,206.

Patented November 8, 1904.

UNITED STATES PATENT OFFICE.

HENRY L. WALLACE, OF WALLINGFORD, CONNECTICUT, ASSIGNOR TO
R. WALLACE & SONS MFG. CO., OF WALLINGFORD, CONNECTICUT,
A CORPORATION.

DESIGN FOR A HANDLE FOR SPOONS, FORKS, OR SIMILAR ARTICLES.

SPECIFICATION forming part of Design No. 37,206, dated November 8, 1904.

Application filed October 6, 1904. Serial No. 227,514 Term of patent 7 years.

To all whom it may concern:

Be it known that I, HENRY L. WALLACE, a citizen of the United States, residing at Wallingford, in the county of New Haven and State of Connecticut, have invented a new, original, and ornamental Design for a Handle for a Spoon, Fork, or Similar Article; and I do hereby declare the accompanying drawing to be a full, clear, and exact illustration of the same, and which said drawing constitutes part of this

specification, and represents a face view of a handle for a spoon, fork, or similar article.

I claim—

The ornamental design for a handle for a spoon, fork or similar article as shown.

HENRY L. WALLACE.
